UNITED STATES PATENT OFFICE.

FREDERICK BRANDT, OF NEW YORK, N. Y.

ALARM ATTACHMENT FOR OVERFLOW-BASINS.

SPECIFICATION forming part of Letters Patent No. 357,307, dated February 8, 1887.

Application filed March 25, 1886. Serial No. 196,511. (No model.)

To all whom it may concern:

Be it known that I, FREDERICK BRANDT, of the city of New York, county and State of New York, have invented a new and Improved 5 Alarm Attachment for Overflow-Basins, of which the following specification is a full, clear, and exact description.

This invention relates to an alarm attachment to be applied to the overflow-basins of 10 refrigerators and to similar purposes. The alarm is constructed in such a manner that when water accumulates to a certain height within the basin it will raise a float and thereby liberate the mechanism which sounds 15 a bell.

The invention consists in the various features of improvements hereinafter more fully pointed out.

In the accompanying drawings, Figure 1 is 20 a sectional side view of the apparatus. Fig. 2 is a back view of plate *b*, and Fig. 3 a back view of the gear mechanism with plate *b* removed.

The letters *a* *b* *c* represent three parallel 25 plates, of which the plates *a* *b* are connected by pins *d*, while the plates *b* *c* are connected by lugs *e*, cut out from the body of plate *b* and bent backward to join plate *c*, to which they are secured by means of rivets or solder. The 30 plate *c* is provided at its top with a hook, *f*, by which it may be suspended over the edge of a basin, *A*. At its bottom the plate *c* has a nose or noses, *g*, to hold it in an upright position.

35 *h* is a spindle passing through and having bearings in plates *a* *b*. This spindle is surrounded by a coiled band-spring, *i*, one end of which is attached to the spindle, while the other end is attached to a fixed drum or shell 40 secured to the front of plate *a*. By revolving the spindle the spring is wound up.

The spindle *h*, to which one end of the 45 band-spring *i* is attached, carries gear-wheel *j*, giving motion to said wheel *j* through an ordinary connection, such as a ratchet-wheel carried by the spindle and a click carried by the gear-wheel, as soon as ratchet-wheel *k* is relieved, when said gear-wheel *j* revolves the ratchet-wheel *k* through an intermediate cog-wheel. The ratchet-wheel *k* bears against a 50 shoulder, *l*, formed near the end of a pivoted hammer, *m*, having a weighted head, *n*. The

revolution of the ratchet-wheel *k* causes the hammer to be swung outward (to the left in Fig. 3) as a tooth of the wheel bears against the shoulder *l*. As soon as the shoulder is 55 liberated the weighted head *n* causes the hammer to swing back, and thus a rapid reciprocating motion is imparted to the hammer.

o is a float pivoted to plate *c* by means of 60 an arm having a downwardly-curved catch, *p*. This catch bears against one side of a pin, *q*, attached to head *n* and projecting through a slot of plate, *b*.

r is a bell against which the hammer strikes. 65 The operation of the device is as follows: The clock-work being wound up, the apparatus is put into position, as in Fig. 1, in such a way that the float *o* projects into the basin. The float is now in its lowermost position and the catch *p* is opposite the pin *q* and locks the clock-work. As soon as the float *o* has risen by an accumulation of water (dotted lines, Fig. 1) the catch *p* will swing 70 down and the pin *q* will thus be liberated to 75 permit the clock-work to move the hammer and to sound the alarm:

I claim as my invention—

1. The combination of bell *r* and plate *c* with spindle *h*, hammer *m*, having shoulder *l* 80 and pin *q*, and with float *o*, catch *p*, gear-wheel *j*, ratchet-wheel *k*, and spring *i*, substantially as specified.

2. The combination of bell *r* and plate *c*, having hook *f* and nose *g*, with float *o*, catch 85 *p*, hammer *m*, pin *q*, spindle *h*, spring *i*, gear-wheel *j*, and ratchet-wheel *k*, substantially as specified.

3. The combination of bell *r* and float *o*, having catch *p*, with hammer *m*, having 90 weighted head *n*, pin *q*, and shoulder *l*, and with spindle *h*, gear-wheel *j*, and ratchet-wheel *k*, that engages shoulder *l*, substantially as specified.

4. The combination of plates *a* *b* *c* with 95 spindle *h*, gear-wheel *j*, ratchet-wheel *k*, spring *i*, hammer *m*, having shoulder *l*, head *n*, and pin *q*, and with bell *r*, float *o*, and catch *p*, substantially as specified.

FRED. BRANDT.
